(57) **CLAIM**

The ornamental design for a scientific instrument, as shown and described.

DESCRIPTION

FIG. 1 is a perspective view of a scientific instrument, showing our new design.

FIG. 2 is a front view of the instrument of FIG. 1.

FIG. 3 is a back view of the instrument of FIG. 1.

FIG. 4 is a left side view of the instrument of FIG. 1.

FIG. 5 is a right side view of the instrument of FIG. 1.

FIG. 6 is a top view of the instrument of FIG. 1; and,

FIG. 7 is a bottom view of the instrument of FIG. 1.

The broken lines in the drawings depict portions of the scientific instrument that form no part of the claimed design.
